UNITED STATES PATENT OFFICE

DANA W. BENNETT, OF SOMERVILLE, MASSACHUSETTS.

DESIGN FOR AN ADVERTISING-CARD.

SPECIFICATION forming part of Design No. 31,952, dated December 5, 1899.

Application filed September 12, 1899. Serial No. 730,273. Term of patent 14 years.

To all whom it may concern:

Be it known that I, DANA W. BENNETT, a citizen of the United States, residing at Somerville, in the county of Middlesex and State of Massachusetts, have invented and produced a certain new and original Design for an Advertising-Card; and I do hereby declare the following to be a full, clear, and exact description of the invention, such as will enable others skilled in the art to which it appertains to make and use the same.

As shown in the drawing, the leading and material features of my design consist in the following: The card, which is flat and substantially of uniform thickness, comprises a rectangular portion symmetrically surmounted on its shorter side by a substantially isos-

celes-triangular portion, of which the base is larger than the shorter side of the rectangular portion. The two portions are paneled. In the upper part of the rectangular portion is a handle-shaped figure, and below said figure is a small rectangular-shaped figure.

Having thus described my invention, I claim as new and desire to secure by Letters Patent of the United States—

The design for an advertising-card, substantially as shown and described.

In testimony whereof I affix my signature in presence of two witnesses.

DANA W. BENNETT.
